BLANK RECEIVING AND DELIVERING TABLE.

1,229,513.

Specification of Letters Patent. Patented June 12, 1917.

Application filed April 28, 1916. Serial No. 94,209.

To all whom it may concern:

Be it known that we, MELVILLE E. PETERS, GEORGE H. FATH, and ALBERT F. MILLER, citizens of the United States of America, 5 residing in the city and county of Denver and State of Colorado, have invented a new and useful Blank Receiving and Delivering Table, of which the following is a specification.

10 Our invention relates to an automatically operating blank receiving and delivery table mechanism for blank gumming machines; and the objects of our invention are:

First, to provide a flat table-like member 15 that is adapted to receive the blanks one at a time from their gumming cylinder and in which the blank is held in place on the table by air suction.

Second, to provide a simple and reliable 20 gummed blank receiving and delivering table. And

Third, to provide a quick receiving and delivering mechanism for gummed blanks that will receive and hold them in a flat 25 horizontal plane and that will deliver and release them automatically at a predetermined point that is adapted to permit the blank to be instantly engaged and advanced 30 into wrapping relation with a box in a box wrapping machine.

We attain these objects by the mechanism illustrated in the accompanying drawings, in which:

Figure 1, is a side view of a portion of a 35 blank gumming machine, illustrating the application of the improved blank delivering table.

Fig. 2, is a plan view of the blank delivery end of the machine.

40 Fig. 3, is a vertical sectional view, enlarged, on the line 3—3 of Fig. 1.

Fig. 4, is a front view of Fig. 3, the clamping nut and washer being removed.

45 Fig. 5, is a sectional view, illustrating the table, one of its supporting rack bars and the gear for operating the same.

Fig. 6, is a side view, illustrating one of the blank grippers in open position, and the mechanism for holding open and for 50 releasing said grippers. And

Fig. 7, is a side view illustrating means for opening said grippers.

Similar letters of reference refer to similar parts throughout the several views.

Referring to the drawings,—

The numeral 1 designates a smooth, flat top table or plate, which may be made of any suitable material, but which we preferably make out of aluminum, and which extends across the machine between its side frames 2 and 3. Consequently this table portion is preferably a flat sheet or blade of aluminum which we will hereinafter call a table.

This aluminum table is secured to a reciprocating supporting frame, which comprises the side rack bars 4 and to which this table is secured at the forward ends of the rack bars. These rack bars have a gear toothed rack portion extending along their lower edges from the rear end of the table, and they extend far enough back into the gumming machine to form a suitable sliding support for the table, and they are slidably supported in suitable bearings 5 that are secured on the side frames 2 and 3. These rack bars are reciprocated in alternate timed relation to the blank feeding, gumming and conveying mechanism of the blank gumming machine, which we do not fully illustrate, but which is fully illustrated in our pending application Serial Number 30,471, filed May 25, 1915, for a blank gumming machine, and while this blank gumming and transmitting mechanism does not appertain directly to the subject matter of our present invention, which is an improved divisional part of that machine, we deem it advisable to refer briefly to it.

To this end the gumming machine of the above mentioned pending application comprises in its main features a blank feeding roller 6, to which the blanks B are fed one at a time by any suitable automatically operating mechanism. From the blank feeding cylinder the blanks are fed onto a blank gumming cylinder 7.

This blank gumming cylinder is provided with a supply of adhesive gum, which as the blanks are fed against it coats their surface that lies against the outside surface of the cylinder with a suitable adhesive gum.

The advancing edge of the blanks feed

one at a time onto an inwardly retreating segment portion 8, of the gumming cylinder. These blanks are carried a short distance partially around the cylinder, to a point where this segment retreats into the interior of the cylinder, and when it does it exposes the edge of the blank B, which is then gripped by a row of blank gripping fingers 9 that are mounted on rotatable bars 9^A, at the advancing end of a plurality of apron conveyers 10. These apron conveyers are arranged into the form of an endless conveyer, which is mounted on a gapped transmission cylinder 11 at one end, and on 15 a roller 12 at its opposite end between which the lower side of the conveyer runs over an idler and tightening supporting mechanism, not shown.

This apron conveyer has a short intermittent traveling movement that is equal to the distances between the centers of each set of blank gripping fingers 9 of the aprons 10, which are positioned at equi-distant distances apart throughout the length of the 25 endless conveyer. These gripper fingers 9 are spring controlled to grip each blank against a bar 13, and they are released by a cam 14 at the transmission cylinder. The finger grippers and the bar fit into a gap 30 15 of the transmission cylinder as they pass around it.

The function of these endless apron gripper fingers is to grip the exposed edge of each blank at the gap of the gumming cylinder against the bar 13 when the gap is 35 opened, and then to carry the blank it grips up over the transmission cylinder, and as they do this the blank is folded in a naturally curved plane down flat on the apron 40 of the grippers that removed it from the gumming cylinder. The blanks all rest on the aprons with their gummed side uppermost. Each blank is then transmitted by intermittent movements of a length to bring 45 each bar 13, centrally over and within a gap in the end turning roller 12, where it makes one of its stops, which particular stopping point we term its blank removing station, and at this blank removing station the bars 50 9^A are partially rotated by mechanism 16, by which the grippers are opened, as shown in Fig. 7, and release the blanks, and when the grippers are thrown back to release the blanks, their supporting rod is automatically 55 held by a ratchet and pawl mechanism 17 that locks the grippers in an open position, and they stay locked in this open position until released in the gap of the transmission cylinder by the cam 14, when springs 60 18 on the said bars 9^A impart a quick partial rotation to the bars, which throws the grippers down to grip a blank to the adjacent bar 13. There are consequently three or more gummed blanks moving by short 65 intermittent movements from the gumming

cylinder to their removing station all the time the machine is running.

The instant before the gripper fingers open and release the blank at this blank removing station, the advancing edge of the blank 70 is gripped by a plurality of air suction operating blank gripping tubes 19. These tubes lift the blanks up and transmit them over and deposit them onto the table 1. These air tubes have a reciprocal stroke 75 movement that does not vary in its distance from where they receive the blanks to where they discharge them, and we call the point which we have marked with an arrow in Fig. 1, the discharging point of the blanks' transmitting system. This point becomes also the blank receiving point of the delivery table, as indicated by x—x in Fig. 2, as the table always receives each blank at 80 this point, which becomes the beginning of the blank delivery movement, and the blank and box registering movement of our blank delivery table.

The toothed rack bars 4 which support the table, are reciprocated by large gears 20, that are mounted on the opposite ends of a shaft 21, that extends across the machine and is journaled at its ends in the side frames 2 and 3 of the machine. One end of this shaft extends beyond the side 3 of the machine and a pinion 22 is mounted on its end. This pinion is engaged by a vertical rack bar 23, which is reciprocally mounted in suitable slideway bearings 24, that are mounted on the side of the side frame 3. 95

To the central portion of this vertical rack bar is pivotally secured one end of a connecting rod 25, the other end of which is connected to a rock lever 26, which will be hereinafter described. 100

The table will accommodate blanks of different sizes, from about two by three inches square to about twelve by twenty inches square, and it is necessary that the advancing edge of each of these widely differing sized gummed blanks should have their advance or forwardly feeding edge deposited directly onto the forward edge portion of the table, and that the advancing edge of the blank be gripped and held firmly to the forwardly advancing edge of the table in such a manner that this edge be again gripped and held until the table is withdrawn from under it on the return stroke of its reciprocal movement, in which case 110 the boxes are applied to the blanks after the table has been withdrawn from the blank. It is also just as necessary that the table grip the blanks and hold them in straight alignment with the ends and sides of the 115 table even when the boxes are applied to the blanks, while they are held on and are supported by the table. 120

Our invention contemplates broadly any and every and all means by which blanks 130

as they are delivered on the table are gripped and held for any predetermined period of time. We preferably however effect this blank gripping, holding and releasing feature of the table in the following manner:

5 Transversely across the table and upon its advancing edge is secured a vacuum box 27, which is provided with a row of air inlet apertures 28. We preferably illustrate six 10 of these apertures, but more or less may be used as desired.

These air inlet apertures extend into the box that is secured transversely along the under side of the edge of the table, as shown 15 by Fig. 5. This box is connected by suitable air tubing 29 with an operative air pump 30, that is mounted on the base plate of the machine, and which is provided with a piston and rod, the rod being connected to the 20 lower end of a rock arm 31, which is operated by a cam, that is secured on one side of a disk 32, that is mounted on a power driven shaft 33. Consequently the advance edges of the blanks have to be deposited by 25 the air suction blank transmitting tubes directly down, over and against these air suction blank apertures, which grip and hold each blank to the table, and the body of the blank lies rearwardly on the table and the 30 centers of the shorter blanks come into a different position from the centers of the larger blanks on the table, and when these gummed blanks are transferred from this table to a box wrapping machine, or if boxes 35 are placed either by hand or by an automatic plunger mechanism, such as is illustrated in our pending application, Serial No. 76,991.

The centers of all sizes of the central body portion of the blanks must be moved to a 40 predetermined point to receive the box. Consequently the various sizes of blanks that our machine will transmit onto this table have to be moved by the table to a central point, which is the same with all sizes 45 of boxes that will bring the center of the blanks directly under the center of the box, and it is necessary that an adjustable variable throw mechanism be employed to move the table as desired to bring the central body 50 portion of each size blank directly in alignment with the center of the box the blank is to be wrapped around, such for instance as the center of the upper and lower plungers of a box wrapping machine, of a style illustrated in our pending application Serial 55 Number 59,860, filed November 5, 1915, for a box wrapping machine.

There are a number of ways in which we 60 can carry out this feature of our invention. We preferably accomplish it however in the following manner:

The rock lever 26 to which the lower end of the connecting rod 25 is attached, is pivotally mounted at its rear end upon a stub 65 shaft 34, which is secured to the adjacent

side frame 3. About centrally of its length, the lever is provided with a roller 35, which enters a cam groove 36, on the outer side of a disk 37, which is mounted on the power driven shaft 33. The forward portion of 70 the lever is curved as shown, and is provided with a slot 38 of suitable length, in which is placed a block 39, having an integral disk 40, which bears against the inner side of the lever, while a threaded stem 41 projects 75 from the outer face of the block, upon which a washer 42 is placed, and a nut 43 is screwed upon the stem, against the washer, whereby the block is securely held at any desired point in the slot 38. A stud 44 projects from the face of the washer 40, and this stud passes through the lower end of the connecting rod 25, which is held thereon by a washer 45, which is secured to the stud by a screw 46. The desired stroke of the 80 85 rack bars 4 is accomplished in the following manner:

The cam 37 is turned to the position shown in Fig. 1, when the roller 35 of the lever 26 is on the lowest point of the said 90 cam; the nut 43 is then loosened and the block 39 is slid back to the inner end of the slot 38, carrying with it the lower end of the connecting rod 25. In this position of the lever, the slot 38 is an arc whose radius is 95 the pivotal point of the connecting rod 25, as will be understood by reference to Fig. 1. The cam is then turned until the roller 35 rests upon its highest point; the lever 26 is then in the position shown in dotted lines, 100 and the rock bar 23 is raised a distance equal to the length of the dotted line Z. If this movement is not sufficient to give the required throw to the rack bars 4, the block 39 is slid forward in the slot 38, until the vertical rock bar 23 is raised high enough to 105 impart the required throw to the bars 4, through the medium of the pinion 22, and gear wheels 20. The block 39 is then clamped to the lever 26, at this point, and by this arrangement the table will be carried 110 forward the exact distance required to bring the centers of the blanks being run, to register with the centers of the plungers of a box wrapping machine. By this arrangement, there is no lost motion, as the rock bar 23 begins to rise, instantly, with the upward 115 movement of the lever 26.

Thus when the table is at the farthest limit of its forward movement, the largest 120 size blanks twelve by twenty will have their central body portion directly in alignment with the center of a box, such as this size of blank would wrap around, and if the box is on the upper plunger of the box wrapping 125 machine, the blank will be released by the table the instant it reaches the full end of its stroke, and will be gripped by an air suction device that is mounted on the box wrapping machine. Then when the table is 130

moved backward instantly after the box machine grippers have gripped the blank, the blank will be left with its central body portion resting on top of the lower plunger.

5 Our table is especially adapted to deliver gummed blanks to our above mentioned box wrapping machine, as is fully described in that application.

10 In the two box and table registering applications above mentioned, an adjustable set of box guiding clips is used to guide the box by hand centrally onto the blank.

15 The forward stroke of the table is adjusted to come under the center of the upper plunger. Consequently our delivery table can be used for delivering gummed blanks of a large number of varying sizes to three different box and blank registering systems. One system is that by which the blank is delivered automatically by the table to a box wrapping machine. Another system is that by which the box is placed by hand on a plunger, which then moves down and glues the bottom of the box to the central body 20 portion of the blank, while it is still gripped by the air suction blank gripping air inlet apertures of the table, after which the plunger moves up out of the box but leaves a stripper bar in it until the plunger has 25 moved entirely out of the box. Then an attendant picks up the box with the blank glued to its bottom, it having been released from the air suction grip of the table the instant the plunger stripper leaves it, and 30 places the box and blank by hand on the upper plunger of a box wrapping machine. The third system is that where the box is registered by hand between guiding clips directly and centrally against the gummed blank, as it is delivered on and is held on the table, and is removed by hand from the 35 table.

The operation of our blank delivery table is as follows:

40 The blanks are fed into the machine to the feed roller and onto the gumming cylinder, where they are coated with gum and are then transmitted onto the conveyer, and from the end of this conveyer, which stops 45 each blank below the air tubes, which pick them up by air suction and transmit them horizontally to and move down with them against the surface of the table, which moves far enough underneath the forward end 50 movement of the tubes to allow them to move down between the air inlet apertures of the table, which deposits the advancing edge of the blank directly down over and against the air suction blank gripping apertures of the table, which grips them and holds them firmly to the table upon which they lie flat. The length of the reciprocal stroke of the table is then adjusted so that 55 the table will deliver the center of the central body portion of the blank directly under

the center of the star Fig. 2, which would be the center of the size of box the blank is intended to wrap by either one of the above named systems of registering the boxes against the center of the blank.

70 Our invention provides a reliable, very quick adjustable stroke air suction gripping blank supporting and holding table, and while we have illustrated and described the preferred construction and arrangement of our invention, we do not wish to be limited to it, as many changes might be made without departing from the spirit of our invention.

75 Having described our invention, what we claim as new and desire to secure by Letters Patent, is:

1. In a blank delivering table for blank gumming machines, the combination of a table made of a sheet or blade of aluminum, 80 provided with a blank receiving station, means for imparting a variable throw stroke from the blank receiving point of the table forward a predetermined distance varying with the size of the blank on the table, 85 whereby said blank is moved and delivered by said table into a box receiving position, means on said table including air suction inlet apertures for gripping the blank at its blank receiving station, by an air suction 90 force, and for holding and releasing it at its box receiving station.

95 2. In a blank delivering table for blank gumming machines, the combination of a table made of a sheet or blade of aluminum, 100 provided with a blank receiving station, means for imparting a variable throw stroke from the blank receiving point of the table forward a predetermined distance varying with the size of the blank on the table, 105 whereby said blank is moved and delivered by said table into a box receiving position, means on said table including air suction inlet apertures for gripping the blank at its blank receiving station by an air suction 110 force, and for holding and releasing it at its box receiving station, said table being provided with recesses in its advance moving edge adapted to permit said blank to be gripped and held in box receiving relation 115 when released by said table and said table has moved on its return stroke from under said blank.

120 3. A gummed blank receiving and delivering table, comprising a table made of aluminum having a smooth flat top, means on said table for gripping a blank at a predetermined blank receiving station, and means for delivering the blank at any predetermined desired point of delivery to receive a 125 box in wrapping relation to it.

130 4. In a gummed blank receiving and delivering table, the combination with a blank gumming machine, provided with means for gumming blanks of different predetermined

- sizes and for conveying them to a table receiving station, with a blank receiving and delivering table of aluminum or other suitable material, said table being provided with
- 5 an air suction blank gripping plurality of air inlet apertures in said table arranged to grip the blanks one at a time at the table's blank gripping station and to hold to it while being forwarded to its delivery point,
- 10 means including a cam actuated air pump operatively connected to said air suction blank gripping apertures of said table, arranged in timed sequence to the blank receiving movements of said table for gripping,
- 15 holding and releasing said blank as desired, and means including gearing and adjustable variable stroke cam actuated mechanism for reciprocating said table from its blank receiving station to any predetermined blank and box registering and wrapping relation.
- 20 5. In a blank receiving and delivering table for blank gumming machines, the combination of the blank delivering table, slide-ways on said gumming machine, rearwardly
- 25 extending rack bars mounted in said slide-ways, a shaft, gears on said shaft meshing with said rack bars, a pinion on said shaft, a vertical reciprocating rack bar meshing with said pinion, means for varying the
- throw of said rack bar whereby a variable throw forward stroke may be imparted to said table, and means including a cam actuated lever mechanism operatively secured to the lower part of said rack bar.
6. The combination with a frame, rack bars slidably mounted therein, a table secured to said rack bars, a shaft mounted in the frame, gears thereon in mesh with the said rack bars, a pinion on the shaft, a rack bar in mesh with said pinion, a connecting rod pivotally connected at one end to said rack bar, a lever pivoted at one end to said frame, the forward portion of which is curved in an arc, of a radius corresponding to the length of said connecting rod, and having a slot of the same curvature, a block adjustably mounted in said slot, and having a pivotal connection with the other end of said connecting rod, and a power operated cam for rocking said lever.
- 30 35 40 45 50
- In testimony whereof we affix our signatures in presence of two witnesses.
